(74) Attorney, Agent, or Firm — Cynthia S. Lamon; Lamon Patent Services

(57) **CLAIM**

We claim the ornamental design for the boat squeegee handle, as shown and described.

DESCRIPTION

FIG. 1 is a perspective view of a boat squeegee handle; FIG. 2 is back side elevation view thereof; FIG. 3 is a front side elevation view thereof; FIG. 4 is a left side elevation view thereof; FIG. 5 is a right side elevation view thereof; FIG. 6 is a top view thereof; and, FIG. 7 is a bottom view thereof.

The broken lines in the drawings depict environment of the boat squeegee handle and forms no part of the claimed design.
